UNITED STATES PATENT OFFICE.

MARTIN McDAID, OF LEITH, SCOTLAND, ASSIGNOR, BY MESNE ASSIGNMENTS, TO
REVERE RUBBER COMPANY, A CORPORATION OF RHODE ISLAND.

MACHINE FOR WINDING THE CORES OF GOLF-BALLS.

1,224,397.

Specification of Letters Patent.

Patented May 1, 1917.

Application filed August 1, 1916. Serial No. 112,492.

To all whom it may concern:

Be it known that I, MARTIN McDAID, a subject of the King of Great Britain, and a resident of 56 Seafield road, Leith, in the 5 county of Edinburgh, Scotland, have invented certain new and useful Improvements in Machines for Winding the Cores of Golf-Balls, of which the following is a full, clear, and exact description.

10 My invention relates to improvements in machines for winding cores of golf balls with rubber thread or similar elastic or resilient material which when covered with the usual gutta percha covering produces 15 the necessary resiliency in the ball as a whole.

The present invention relates to improvements in such machines and involves an improved and simplified construction over that 20 disclosed in my prior United States Patent No. 838,202, dated December 11th, 1906.

For a detailed description of the form of invention which I deem preferable, reference may be had to the following specification 25 and the drawings forming part thereof in which—

Figure 1 is a front view of the machine; Fig. 2 an end elevation thereof showing the right-hand end of the machine as illustrated in Fig. 1.

Fig. 3 is a plan view thereof; and

Fig. 4 is a cross-sectional view taken substantially on the line 4—4 of Fig. 1.

Referring to the drawings the numeral 1 35 indicates a suitable table or standard upon which the machine is secured by a bolt or screw 2 passing through the frame 3 of the machine. The rear of the frame 3 is provided with two upstanding lugs or ears 4 and 5 forming bearings for a main driving shaft 6. This driving shaft is provided at 40 one end with a hand wheel 7 and also with fast and loose pulleys 8 and 9 respectively, over which a driving belt 10 may be operated. The opposite end of the shaft 6 has 45 fixed thereto a main driving gear 11 which meshes with two sets of pinions 12—13 and 14—15. The pinions 14—15 are fixed respectively to a solid shaft 16 and to a concentric tubular shaft 17, which are supported in bearings 19 and 20 fixed to the sides of the frame 3. The opposite end of the shaft 16 has fixed thereon a roughened or knurled disk or wheel 21, and the tubular 55 shaft 17 has fixed thereon adjacent the wheel 21 a similar knurled or roughened wheel 22.

The gears 14 and 15 respectively have different numbers of teeth so that when driven by the gear 14 they will revolve at slightly different speeds. In the present instance 60 the gear 14 has a smaller number of teeth than the gear 15 whereby the gear 14 will be driven at a slightly greater rate of speed than the gear 15. This will cause the knurled wheels 21 and 22 to revolve at corresponding rates of speed respectively, the wheel 21 rotating at a slightly higher rate 65 of speed than the wheel 22.

On the shaft 6 are pivoted a pair of horizontally extending arms 23 and 24 which at 70 their outer end are fixed to a long tubular bearing 25. Through this bearing pass solid and tubular shafts 26 and 27 similar to the shafts 16 and 17. The pinion 12 is attached to the end of the solid shaft 26 and 75 the pinion 13 to the end of the tubular shaft 17. The opposite end of said shafts carry the knurled wheels or disks 28 and 29 respectively. The gear 12 however, is provided with a greater number of teeth than 80 the gear 13 which causes it to rotate more slowly than the gear 13. This will cause the knurled wheel 28 to rotate more slowly than the knurled wheel 29.

It will now be seen that since the knurled 85 wheel 21 rotates at substantially the same speed as the knurled wheel 29, and the wheel 22 at substantially the same speed as the wheel 23, the former pair rotating slightly faster than the latter pair, a ball 90 retained between the pair's of wheels will be rotated slowly about an axis which passes through the axes of two shafts. Thus the elastic thread will be continually wound in different great circles about the core, so distributing the thread evenly over the whole body of the ball.

The ball being manufactured is held in position under spring pressure and in correct relation to the knurled wheels by the 100 following means:

An arm 30 is pivoted to the end of the machine as at 30', the opposite end thereof is pivoted to the ends of two upwardly extending arms 31 and 32, the upper ends of each 105 of which are in turn pivoted to the arms 33 and 34 whose opposite ends are also pivoted on the end of the machine at 35 and 36. The pivot between the arms 31 and 33 carries a small roll 37, and the pivot between the 110 arms 32 and 34 carries a small roll 38. A coil spring 39 connects the arms 31 and 32 and

the tension thereof tends to draw the same toward each other, thereby forcing the rolls 37 and 38 in the same direction. The rolls 37 and 38 are separated from each other by an upward movement of the tubular bearing at 25 by movement of the handle 46 attached thereto, the connection for this purpose is as follows:—

The arm 24 carries a lug 41 through which passes a pin 42 preferably in the form of a screw to permit of ready adjustment. A connecting link 43 is pivoted on said screw 42 and is connected at its lower end with the arm 32 by means of the pivot 44. It will now be apparent that when the handle 40 is raised (Fig. 4) the link 43 will also be raised thereby raising the arms 31 and 32 which being controlled by the pivots 30, 35 and 36 will cause the rollers 37 and 38 to separate against the tension of the spring 39. The wheels 28 and 29 being at the same time elevated a core may be easily inserted between the same and said rollers 37 and 38, which when the handle 40 is released will position the ball correctly between the knurled wheels 21, 22, 28 and 29. A strand 45 of rubber thread or similar material may be first wound for a few turns about the core before being inserted in the machine. The winding is then started accurately by turning the hand wheel 7 slowly until the winding has progressed to a sufficient point to warrant increasing the speed. Thereupon the belt is shifted to the fixed pulley 8 and the machine operated under its power until a sufficient quantity of thread has been wound upon the core. The end of the thread is then secured to the ball and the same removed from the machine after which it may be treated by having the outer covering supplied in the usual way.

The numeral 46 indicates a guide roll over which the thread 45 passes and 47 a cylindrical grooved pin for guiding and tensioning the thread.

Having thus described this form of my invention, what I claim and desire to protect by Letters Patent is:—

1. A ball winding machine, comprising a pair of friction wheels adapted to contact with one side of a ball, means to hold said ball on the peripheries of said wheels, and means for rotating said wheels in the same direction at different relative constant peripheral speeds.

2. A ball winding machine, comprising pairs of friction wheels adapted to contact with opposite sides of a ball, the wheels of each pair being located adjacent each other, and means for rotating the wheels of each pair at different relative peripheral speeds to turn said ball on an axis at an angle to respective axes of said wheels.

3. A ball winding machine, comprising pairs of friction wheels adapted to contact with diametrically opposite sides of a ball, the wheels of each pair being located adjacent each other, and means for positively rotating the wheels of each pair at different relative peripheral speeds to turn said ball on an axis at right angles to the respective axes of said pairs of wheels.

4. A ball winding machine, comprising pairs of friction wheels adapted to contact with diametrically opposite sides of a ball, parallel shafts on which said wheels are carried, means connecting said shafts for rotating one wheel of each pair at the same speed, and the other wheels of each pair at greater speeds.

5. A ball winding machine, comprising pairs of friction wheels adapted to contact with diametrically opposite sides of a ball for rotating the same, parallel shafts on which said wheels are carried, pinions on said shafts, the pinions for the respective shafts of each pair of wheels having different numbers of teeth, and a common driving gear meshing with all of said pinions.

6. In a ball winding machine, friction wheels adapted to contact with opposite sides of a ball for rotating the same, guide rollers movable toward and away from the space between said wheels, and means for moving said rollers simultaneously and equally in said directions.

7. In a ball winding machine, friction wheels adapted to contact with opposite sides of a ball for rotating the same, guide rollers movable toward and away from the space between said wheels, levers pivoted on the frame of said machine and on the free ends of which said rollers are carried, and a toggle connection between said levers whereby they are moved simultaneously and equally in opposite directions.

8. In a ball winding machine, friction wheels adapted to contact with opposite sides of a ball for rotating the same, a movable support for one of said wheels, guide rollers movable toward and away from the space between said wheels, levers pivoted on the frame of said machine and on the free ends of which said rollers are carried, toggle connections between said levers whereby they are moved simultaneously and equally in opposite directions, and a connection between said wheel support and said toggle whereby said rollers are moved when said wheel support is moved.

Signed this 14th day of July 1916 at Edinburgh, Scotland.

MARTIN McDAID.
